UNITED STATES PATENT OFFICE.

FRANCIS J. DOYLE, OF CHICAGO, ILLINOIS, ASSIGNOR TO N. V. HAYWARD.

ENGINE.

1,390,281.

Specification of Letters Patent. Patented Sept. 13, 1921.

Application filed October 15, 1917. Serial No. 196,590.

To all whom it may concern:

Be it known that I, FRANCIS J. DOYLE, a citizen of the United States, residing in the city of Chicago, county of Cook, and State of Illinois, have invented certain new and useful Improvements in Engines, of which the following is a specification.

This invention relates to improvements in engines and has among its salient objects to provide a construction in which the expansion of the gases not only exerts a push but also a pulling action on the piston; to provide a construction in which the stroke of the piston is always upward; to provide a construction in which the piston and cylinder each have an independent bodily movement in opposite directions on any given stroke and are connected to operate synchronously; to provide a construction in which the explosion or expansion of the gases move both the piston and cylinder so as to successively allow the intake of the charge, compression of the charge, explosion of the charge and expansion and also exhaustion of the charge; to provide a construction in which the exhaust is in the case of an explosive mixture drawn out of the cylinder by the aid of a vacuum created by a pump so as to insure a rapid and complete exhaustion; to provide a construction in which during the first part of the stroke the explosion or expansion takes place then the exhaust gases are removed, a fresh charge then taken in and compressed; to provide a construction in which there is a positive action at each move of the piston and at the end of each piston stroke; to provide a construction in which no valve mechanisms are used except in the action between the pistons and ports themselves; to provide a construction which practically eliminates vibration of the engine; to provide a construction in which the gas is so measured as to insure at all times the proper mixture and in which the necessity of a carburetor is eliminated; to provide a construction in which the spark plugs are so arranged as to prevent premature explosions, the circuit through the plugs being closed by the cylinder itself; to provide a construction in which the engine may be so constructed as to bodily rotate if desired and to provide a construction in which a single piston and cylinder have the efficiency of a normal four cylinder construction; to provide means for water cooling the

cylinders after explosion if so desired; and in general to provide a simple and improved construction of the character referred to.

In the drawings:

Figure 1 is a top plan view of my engine 60 with parts broken away in sections to show the details of construction and reduce the size of the drawings.

Fig. 2 is a vertical sectional view taken on indirect lines 2—2 of Fig. 1 and looking 65 in the direction of the arrows, parts being broken away.

Fig. 3 is a vertical sectional view through one of the cylinders.

Fig. 4 is a side elevation with the gearing 70 removed.

Fig. 5 is an enlarged transverse sectional view through the cylinder blocks, on an enlarged scale.

Fig. 6 is an enlarged sectional view of one 75 of the gas compression pumps.

Referring to the drawings, 1 designates the base support for the engine, on which are mounted standards 2 and 3. Through these standards is bolted or otherwise suitably secured the cylinder block castings designated as a whole 4. In this cylinder block casting is formed a pair of cylindrical castings 5 and 6 respectively. In each of these casings is mounted a reciprocating cylinder member 7 80 having a side wall 8 and closed ends 9 and 10. Each of these cylinders slide in its stationary casing. Preferably each movable cylinder is provided with a plurality of annular packing ring 10, 10. In each cylinder 90 is mounted a reciprocating piston 11, having positively extending piston rods 12 and 13. These piston rods 12 and 13 may be and preferably are formed integrally as one continuous rod, although they might be formed 95 if desired in two pieces. Each piston rod extends through suitable bearings 14 and 15 in the heads 9 and 10 of the movable cylinders and is connected by a link 16 to the crankshafts 17 and 18.

The movable cylinders are likewise connected at either end to the respective crankshafts by means of a pair of connecting links or rods 19 and 20, it being understood that there is a pair of these at either end of each cylinder. These links are pivoted as shown at 21 to the heads of the movable cylinders and at 22 to the crankshaft. As will be seen more clearly in Fig. 1, the connections between the movable cylinders and the crank- 100 105 110

shafts are such that, as the piston moves in one direction, the movable cylinder moves in the opposite direction.

Describing now the port arrangements for

- 5 the cylinders, each stationary cylinder is provided with a single inlet 23, which is of sufficient size to permit of a proper charge entering the cylinder. Each inlet port is adapted to coöperate with suitable inlet
- 10 ports 24 in the upper side of the movable cylinder. The arrangement is such that these ports 24 register with the port 23 in the stationary casing at the proper time. The movable cylinder is also provided with a plurality of exhaust ports 25, 25, which coöperate with exhaust ports 26 in the stationary cylinder. These exhaust ports 26 are connected to a common exhaust chamber 27 by means of a plurality of exhaust ducts 28, which are
- 15 formed on the outer side of the stationary casing and all lead to said common exhaust chamber 27. To the exhaust chamber 27 is connected a vacuum pump 29, which pump is actuated through a counter shaft 30, carrying a pinion 31 and driven through one of the constantly rotating trains of gears hereinafter more fully described. The exhaust pump serves to facilitate the very rapid exhaustion of the gases where an explosive
- 20 mixture is used. Where a motor fuel such as steam is used, this exhaust pump might be dispensed with.

As a feature of my invention, I provide means for introducing the gaseous mixture into the cylinder. This is accomplished by a pump designated as a whole 32. This pump comprises a pump cylinder 33, in which is mounted a pair of pistons 34 and 35. The piston 34 is connected by a piston rod 36 to a bracket 37 secured to the links 19 and 20. The piston 35 is connected to an arm 38 by a piston rod 39, the latter being pivoted at 40 to the piston and at 41 to the arm. The arm 38 is secured to the link 16.

- 45 Describing now the manner in which the gas and air enter the pump cylinder, I provide a pair of supply pumps 42 connected to a main inlet pipe 44 by pipes 43. The cylinder 32 is provided with inlet ports 45 and 46, which are controlled by ports 47 and 48, carried by shell like fins 49 and 50, secured to the inner ends of the respective pistons. Inasmuch as these fins pass each other in the inward movement of the pistons, they are opposite each other or lie in different planes or different segments of the circle and each piston is recessed as shown at 51 to receive the fin of the opposite piston. Air is admitted to the cylinders through ports 52, which are controlled by the pistons themselves. The arrangement is such as to form the proper gaseous mixture for induction into the cylinder, thus dispensing with the necessity of a carburetor. The gaseous mixture is ignited by spark plugs 53 and as a

feature of construction, a circuit is closed through the spark plugs by the movable cylinder wall through suitable contacts 54 carried by the movable wall.

Crankshafts are mounted in suitable bearings 55 carried by standards 56, supported on the bed plate. Between the crankshafts are mounted supporting bars 57, 58 and 59, which primarily serve as bearings for gears. Describing first the high gears, on each 75 crankshaft are secured gears 60, which mesh with idle gears 61, which in turn mesh with a central gear 62. The idle gears 61 are mounted on stub shafts 63 carried by the bars 57 and the frame of the engine respectively.

Describing the gears for driving in reverse, on the crankshafts are mounted gears 68, which mesh with idle gears 69, which in turn mesh with a second set of idle gears 85 70 which drive the central gear 71. The gears 69, 70 and 71 are mounted on suitable stub shafts carried by the bar 59. The central gears are loose on the drive shafts 72 and 73. Between each set of high and low 90 gears on these shafts is mounted friction disks 74 and 75, which are actuated by suitable clutch mechanism, which may be of any well known construction. The reverse gears are controlled by clutch disks 78 actuated 95 by clutch lever 79. The friction disks are arranged in a well known manner so that the low gears will not be in driving relation with the drive shafts at the same time the high gears and vice versa.

In the operation of the engine, it will be noted that the piston has driving action in both directions of movement, and also that not only the pistons but the cylinders each have independent bodily movements and are actuated in timed relation.

I claim as my invention:

1. In an engine, the combination with a pair of stationary cylinders, a pair of movable cylinders reciprocating therein, a piston for each movable cylinder provided with piston rods projecting through both ends of the cylinder and secured to a corresponding crankshaft and actuating mechanism whereby each piston and its corresponding cylinder move simultaneously in opposite directions.

2. In an engine, the combination with a stationary cylinder, a movable cylinder reciprocating therein, a piston for the movable cylinder provided with piston rods at both sides of the piston and projecting through the ends of the cylinder and secured to a corresponding crankshaft and actuating mechanism whereby the piston and a corresponding cylinder move simultaneously in opposite directions.

3. In an engine, the combination with a pair of stationary cylinders, of a pair of movable cylinders reciprocating therein and

operably connected at both ends with crank shafts, a piston for each movable cylinder provided with piston rods extending through both ends of the cylinders and having driving connections with said crank shafts, actuating mechanism whereby each piston and its corresponding cylinder move simultane-

ously in opposite directions, inlet and outlet ports in the cylinder registering with inlet and outlet ducts, said outlet ducts communicating with a common exhaust chamber, and means for feeding fresh fuel to the cylinders. 10

FRANCIS J. DOYLE.
